(57) **CLAIM**

The ornamental design for a bottle, as shown and described.

DESCRIPTION

FIG. 1 is a top, front, left side perspective view of a first embodiment of a bottle showing my new design;

FIG. 2 is a rear elevational view thereof;

FIG. 3 is a right side elevational view thereof;

FIG. 4 is a front elevational view thereof;

FIG. 5 is a left side elevational view thereof;

FIG. 6 is a top plan view thereof;

FIG. 7 is a bottom plan view thereof;

FIG. 8 is a rear, right side, and bottom perspective view thereof;

FIG. 9 is a top, front, left side perspective view of a second embodiment of a bottle showing my new design;

FIG. 10 is a rear elevational view thereof;

FIG. 11 is a right side elevational view thereof;

FIG. 12 is a front elevational view thereof;

FIG. 13 is a left side elevational view thereof;

FIG. 14 is a top plan view thereof;

FIG. 15 is a bottom plan view thereof; and,

FIG. 16 is a rear, right side, and bottom perspective view thereof.

The dashed line showing in the drawings is for illustrative purposes only and forms no part of the claimed design. The dot-dash-dot line showing in the drawings defines the boundary of the claim and forms no part of the claimed design.
